(57) **CLAIM**

The ornamental design for a carpet system with dual pile height, as shown and described.

DESCRIPTION

FIG. 1 is a perspective view of a carpet system with dual pile height;

FIG. 2 is a top view thereof;

FIG. 3 is a bottom view thereof;

FIG. 4 is a first side view thereof;

FIG. 5 is a second side view thereof;

FIG. 6 is a third side view thereof; and,

FIG. 7 is a fourth side view thereof.

The subject matter in FIG. 1 shown in dotted lines indicates environmental subject matter that forms no part of the claimed design.
